SELECTING AND PRINTING APPARATUS

Edward E. Kleinschmidt, Highland Park, Ill.

Application August 13, 1936, Serial No. 95,883

61 Claims. (Cl. 178—25)

The present invention relates to selecting and printing apparatus for use in telegraph circuits and the like and, more particularly, to apparatus of the type in which the selection of characters to be printed is controlled by permutation code signals.

Selective and functional devices heretofore employed in telegraph receivers and like devices have involved mechanical and electrical apparatus which by reason of its complexity has given rise to complications in operation. The selecting mechanism and associated assemblies of the present invention as embodied in telegraph printing apparatus by way of example operates in accordance with new and simplified principles which permit the entire apparatus to be greatly simplified and to operate positively in accordance with received signals.

Accordingly, a primary object of the present invention is to provide a novel form of selecting mechanism embodying the new principles of operation hereinafter disclosed. More specifically, an object of the present invention is to provide a new and simplified form of receiver embodying a selection mechanism of the present invention in which the code impulses act to effect stops that directly and progressively position a printing member so that a character is brought into the ultimate printing position when the last code signal of a code combination or group is received.

A further object of the present invention is to provide a novel and simplified receiver and printer embodying a new form of selecting mechanism adaptable to high speed printer operation and eliminating means hitherto considered necessary for storing a selection or providing overlap for the printing action.

Still a further object of the present invention is to provide a novel and simplified printer embodying novel mechanism for automatically performing a plurality of functions after receipt of the last code signal of a code combination or group of signals.

Another object of the present invention is the provision of a novel form of selector or stop lever embodying a double pivot action whereby the action of the printer is considerably simplified and improved.

A further object of the present invention is to provide a simplified combination of a stop wheel and associated operating mechanism whereby much of the apparatus hitherto considered necessary is eliminated.

Still a further object of the present invention is the provision of a novel and simplified form of

ribbon feed and ribbon reversing mechanism wherein proper operation of the ribbon in conjunction with the printing mechanism is assured at all times.

Still further objects of the present invention are to provide novel and simplified mechanisms to select and operate the printer functions such as shift, unshift, line space, carriage return, and the like.

The foregoing and other objects of both general and specific nature will appear in the following disclosure of preferred forms of my invention and from the terms of the appended claims.

In the drawings:

Figure 1 is a plan view of a preferred embodiment of my invention showing the selecting mechanism and the function operating mechanism associated therewith in a typewheel printer.

Figure 2 is a side elevation of the apparatus of Figure 1, showing the selecting mechanism in detail and its manner of cooperation with a signal receiving magnet.

Figure 3 is a front elevation of the apparatus of Figure 1, showing portions of the selecting and printing mechanisms.

Figure 4 is a side elevation of the apparatus of Figure 1 on the side opposite to that shown in Figure 2 showing the printing, inking and shifting mechanism.

Figure 5 is a section of the apparatus taken on the line 5—5 of Figure 1 with a showing of the motor and gears added, showing the operating bails and the function controlling mechanisms.

Figures 6, 7 and 8 show various positions of the selecting levers.

Figures 9 to 15 inclusive show the manner of operation of the selecting levers in connection with the cams and the stop wheel.

Figures 16 to 18, inclusive, show details of the stop lever and its manner of operation with the armature lever.

Figure 19 is a time sequence chart showing the time relation of the various elements.

Figure 20 is a plan view of the magnet of the apparatus of Figure 1.

Figure 21 is a front elevation of the magnet of Figure 1 showing the pole faces.

Figure 22 is a detail of the armature preferably employed in connection with the magnet of Figures 20 and 21.

Figure 23 is a plan of a preferred modification of the present invention employing the same selector mechanism as previously described but with different function operating mechanism.

Figure 24 is a section taken on the line 24—24 of Figure 23.

Figure 25 is a side elevation of the device showing the modified function operating mechanism 5 of Figures 23 and 24.

Figure 26 is a detail of the function operating mechanism of Figure 25.

Figure 27 is a further detail of the function operating mechanism of Figures 25 and 26 showing 10 the dual cam assembly.

Figure 28 is a side elevation of the printing mechanism of the printer of Figures 23, 24 and 25.

Figure 29 is a detail of a portion of the shift 15 mechanism of the printer of Figures 23, 24 and 25.

Figure 30 is a detail of a portion of the unshift mechanism of the printer of Figures 23, 24 and 25.

Figure 31 is a plan of a further preferred embodiment 20 of the present invention as embodied in a page printer.

Figure 32 is a rear elevation of the printer of Figure 31.

Figure 33 is a section taken on the line 33—33 25 of Figure 32.

Figure 34 is a detail of the carriage return mechanism of the printer of Figures 31 to 33, inclusive.

Figure 35 is a detail of the carriage mounting 30 of the printer of Figures 31 to 33, inclusive.

Figures 36, 37, 38 and 39 illustrate the type bar selection and operating mechanism of the printer of Figures 31 to 33, inclusive, in various positions.

Figures 40, 41 and 42 illustrate the operation of 35 a function of the printer of Figures 31 to 33, inclusive, with the elements in various positions.

Figure 43 is a view of the elements of Figure 37 as viewed in side elevation.

Figure 44 is a view of a portion of Figure 41 40 as viewed in plan.

Figure 45 is a detail of the ribbon feed and reversing mechanism.

Figure 46 is a detail of the ribbon feed operating cam.

Figures 47, 48, 49 and 50 illustrate a manner in which the selector of the present invention may be applied to code bar operation.

Figure 51 illustrates a manner in which the 50 selector of the present invention may be applied in a manner to selectively open and close electrical contacts to operate any desired mechanisms.

Figure 52 is a side elevation of a modified form 55 of inking device for a typewheel printer of the type shown in Figures 4 and 28.

Figure 53 is a plan view of the device of Figure 52 with the typewheel removed.

Figure 54 is a partial section of the device of 60 Figure 52 with the typewheel removed taken on the line 54—54 of Figure 53.

Referring to a preferred embodiment of my invention illustrated in Figures 1 to 22, inclusive, and with particular reference to Figures 1, 2 and 65 3, motor 1 has attached to its shaft pinion 2 driving gear 3 which in turn drives a train of gears 4 and 5. Gears 3 and 5 are loosely mounted on shafts 6 and 7, respectively, and tend to revolve such shafts through friction clutches 8 and 70 9 of substantially identical construction. Shafts 6 and 7 are mounted to rotate in a frame comprising side plates 11 and 12 connected by cross members 13 and 14, plate 11 having reinforced foot plate 15. Plate 12 is of skeleton design and is 75 supported entirely by cross members 13 and 14.

Shafts 6 and 7 are mounted in bearings 16 in the upper edges of plates 11 and 12 and held in place by cap members 17 secured by screws 18 or similar means. Motor 1 is supported with reference to plates 11 and 12 by any suitable means. 5 Gear 4 is an idler gear mounted on stud shaft 10.

As shown in Figure 1, friction clutch 8 comprises plate 19 secured to collar 21 which is fastened by set screw 22 to shaft 6, friction composition 23 lying between the face of friction plate 10 19 and an oppositely disposed plate 24 which is maintained in engagement with friction composition 23 by means of spring 25 engaging a face of gear 3. The plate 24 is secured to rotate with gear 3 by jaw clutch 26 shown in Figure 3 in 15 connection with clutch 9. A second friction coupling comprising plate and collar assembly 27 fixed to gear 3, friction composition 28, and plate 29 fixed to shaft 6 is also preferably employed.

Cam assembly 31 is secured to shaft 6 to rotate therewith through a suitable collar and pin arrangement shown at 32. Cam assembly 31 comprises a series of five cams 33, 34, 35, 36, and 37 arranged with their operating lobes 38 (Fig. 2), of which each cam has one, approximately 55 25 degrees apart, each cam being shaped and arranged to operate in connection with a stop or selecting lever, the corresponding selecting levers being shown at 39, 41, 42, 43 and 44, respectively.

Cam assembly 31 further comprises cam 45 30 arranged to cooperate with normal stop lever 46; and cam 47 arranged to cooperate with latch release lever 48, levers 46 and 48 being pivotally mounted on stud 49 secured in side plate 11. Levers 39, 41, 42, 43 and 44 are also mounted 35 on stud 49 but have an elongated bearing aperture 51 as shown in detail in Figures 6, 7 and 8, so that they are permitted a certain amount of displacement as well as rotation at the bearing point. The cams of assembly 31 and the levers 40 upon which they act are preferably spaced by suitable washers 52 to allow of independent movement of the levers and to space the cams in accordance with the levers. The levers may be secured in place by nut 53 secured on the end 45 of stud 49. A latch release lever 48 and cam 47 is provided to release the last selected lever 39 to 44 after the selecting operation is completed. Slightly in advance of the operation of latch release lever 48, cam 45 operates normal 50 stop lever 46 to place its extension in the path of rotating stop 88 as shown in Figures 2 and 3.

Stop plate 54 is secured to cam assembly 31 by a pair of clamping screws 55 as shown in Figure 2, the holes in stop plate 54 through which 55 screws 55 pass being slightly elongated, as illustrated in Figs. 2 and 16, so as to permit of orientation of stop plate 54 with respect to cam assembly 31 for the purpose of setting cam assembly 31 relative to the selective levers 39, 41, 42, 60 43 and 44 in proper relation to the received signals, pointer 56 being provided on stop plate in combination with scale 57 on the cam assembly to aid in orientation. Stop plate 54 is provided with projecting lugs 54' and 55' for a purpose 65 to be later described.

As shown in Figures 2, 16, 17 and 18, start and stop lever 58 is pivoted on stud 59 secured in side plate 11 and is provided with latch extension 61, second extension 62' and cam faced extension 70 63'. Spring 64, secured to start and stop lever 58 at 65 and to side plate 11 at 66, acts upon stop lever 58 to normally hold extension 61 in engagement with projection 62 fixed to armature lever 63 pivoted on stud 64' secured in side plate 75

11. Latch extension 61 and projection 62 are formed with sufficient clearance so that when on the release of armature lever 63, latch extension 61 has dropped behind projection 62, they 5 do not engage each other when armature lever 63 is operated. When stop lever 58 operates to replace latch extension 61 on projection 62, it momentarily operates armature lever 63 slightly. Electromagnet 70, connected to a transmitting circuit by wires 66' is secured to plate 11 by bracket 67 and screws 68. Magnet 70 is normally energized in accordance with the present practice of operating this type of telegraph receiver and when energized attracts armature lever 63 as shown in Figure 2. Spring 69 is secured to armature lever 63 at 71, the opposite end of the spring being secured to bolt 72, capable of adjustment in bracket 73 secured to plate 11 by lug 74 and screws 75, thus enabling adjustment of spring 69. Bracket 73 also carries adjustable bolt 76, the end of which is arranged to limit movement of armature lever 63 in one direction, movement of the armature lever in the opposite direction being limited by bolt 77 25 mounted in a suitable threaded lug 78 on side plate 11. Each of bolts 72, 76 and 77 is preferably provided with a lock nut 79 as shown to enable the locking thereof when in adjusted position.

30 Fulcrum plate 81 is secured to the upper extremity of armature lever 63 and is arranged to cooperate with levers 39, 41, 42, 43 and 44, as shown in Figures 6, 7 and 8 in a manner to be later explained.

35 With reference to Figure 6 (wherein the fingers of stop wheel assembly 101 are not shown) and Figures 7 and 8 wherein stop or selecting lever 39 is shown by way of example, it is assumed that stop wheel 101 has revolved 180 degrees. Lever 39 in Figure 6 is shown in normal position with elongated aperture 51 therein bearing against the lower edge of stud 49 and the upper edge of lever 39 bearing against stop 82, the lever being held in that position by spring 46 83 secured to the lever by collar 84 and secured to the frame of the printer through stud 85'. Each of the selecting levers is provided with a like spring 83 to maintain the levers in their normal position resting against post 82 and the lower 50 surface of bearing stud 49. Springs 83 are preferably staggered as shown in Figure 3 for compactness.

45 In Figure 7, lever 39 is shown in the selected position wherein its upper edge is forced out of contact with stop 82 by the action of its cooperating cam 33, aperture 51 being slightly displaced with reference to stud 49, lever 39 pivoting about plate or fulcrum 81. In this position, it will be noted, that latch lever 85 through plate 86, which extends the width of the lever assembly, locks the lower side of lug 87 of lever 39 to maintain it in its selective position when engaged by stop 102 of a stop wheel which it is assumed has revolved 180 degrees in a manner 60 to be later described. Each of the selecting levers is preferably formed with a notch 89 to facilitate engagement by fulcrum 81. The engaging faces of the notch 89 and the fulcrum 81 are formed so that the fulcrum 81 will be locked 65 to prevent movement thereof when they are in engagement. This feature is to insure the completed motion of lever 39 after it has engaged with the fulcrum 81 regardless of whether or not magnet 70 has in the meantime become de- 70 energized. Likewise the outer face of the notch 75

89 will prevent the fulcrum 81 from moving after the lever 39 has been moved downward slightly thereby insuring the completion of the downward movement of the lever 39 regardless of whether or not magnet 70 has become energized before such movement is completed. This arrangement of the faces of the fulcrum 81 and the notch 89 makes possible an operation which is termed point selection in apparatus of the type described herein without special means therefor. 10

15 In Figure 8, which represents the unselected position of lever 39, cam 33 has forced lever 39 out of engagement with stop 82 and aperture 51 is displaced with reference to stud 49. Since fulcrum 81 is out of contact with lever 39, the left end of the lever moves downward about plate 86 as a pivot. Plate 86 in this instance operates both as a pivot and lock.

20 As shown in Figure 2, latch lever 85 is pivoted on stud 91 secured to plate 11 and normally held against stop 92 by spring 93 secured to an extension of latch lever 85 as at 94 and secured to the frame of the printer as at 95. As cams 33 to 37 pass over stop levers 39, 41, 42, 43 and 44, the latter are moved momentarily in succession, pivoting on fulcrum 81 whenever magnet 70 is energized. The pivoting stop lever will operate latch lever 85 and become itself latched on plate 86. In operating latch lever 85, the normal stop lever 46 or any previously set stop 30 lever will be released, and be returned to normal position by its spring 83.

35 Referring now to Figures 1, 2 and 6 to 15, inclusive, the selector levers are set in accordance with the code signals received on magnet 70 in the following manner.

40 Gear 3 is revolved by motor 1 at a constant speed and in approximate timed relation with the speed of a signal transmitter not shown. Gear 3 tends to rotate shaft 6 through friction clutch 8, but shaft 6 is normally held stationary by engagement of lug 55' with extension 62' of stop lever 58 which is released upon the receipt of a start signal as will be later shown.

45 As is well known, a group of start-stop permutation code signals, by which it is intended to operate this receiver, consists of a start signal, five selecting signals, and a stop signal. The start signal is an interruption in the circuit, and the stop signal is a closing of the circuit. The 50 five selecting signals are either current or no current, depending upon the characters to be selected, as for instance, the letter A consists of two current and three no-current signals.

55 To set the selector levers in accordance with the code signals comprising the letter "A" as above set forth, magnet 70 is deenergized by the start signal, releasing armature lever 63, thereby permitting projection 61 of start and stop lever 58 to fall in the rear of projection 62 whereupon 60 spring 64 draws start and stop lever 58 against stop 58' and disengages extension 62' from lug 55' on stop plate 54, permitting shaft 6 to revolve with gear 3. In this position, lever 46, which is only capable of rotation about pivot 49, is in 65 contact with cam 45. Plate 86 accordingly is over the ends of the remaining levers as in Figure 6.

70 The first selecting signal, being a current impulse, will cause magnet 65 to attract armature lever 63 and place pivoting plate 81 into fulcruming position as shown in Figure 6. Cam 33 (Fig. 14) then depresses stop lever 39, causing it to fulcrum on pivoting plate 81 as in Figure 7, 75

forcing the upper cam face of latch extension 87 upward and latch lever 85 outward. This action causes latch bar plate 86 to release stop lever 46 which is returned to its normal position 5 by its spring 83. Immediately thereafter spring 93 replaces latch bar 85 under stop lever 39 as shown in Figure 7.

The second impulse received on magnet 70, also being "current" attracts armature lever 63 10 and continuous rotation of shaft 6 will cause cam 34 (Fig. 13) to engage stop lever 41 and cause it to operate latch bar 85 to first release the previously selected stop lever 39 and then become itself latched on the top of latch bar 85. 15 The next signal received on magnet 65, being a "no current" impulse, will permit armature lever 63 to retract so that fulcrum 81 will assume the position shown in Figure 8, cam 35 (Fig. 12) 20 engaging stop lever 42 to operate it. Since pivoting plate 81 is out of engagement with stop lever 42, the latter will be moved downward, pivoting at the point of latch extension 87 and latch bar plate 86 and will therefore not operate latch bar 85 after cam 34 has passed out of 25 engaging position, lever 42 will return to its normal position. The two following signals, being also of "no current" character, will operate on magnet 70 and armature lever 63 in the same manner as has just been explained, and no setting of stop levers 43 and 44 takes place. 30

Stop lever 41 will remain in its set position until cam 47 engages the lever 48 to operate latch lever 85. Before doing this, however, cam 45 will operate stop lever 46, setting the same 35 in stop position with relation to latch lever 85 and holding it there until lever 48 completes its function. Such operation is possible by reason of the relatively long contact face of cam 45 which accordingly extends its period of contact 40 with lever 46. A time sequence chart illustrating the time relation of the various operations is shown in Figure 19.

After the selecting operation is completed, lug 54' on stop plate 54 engages with cam faced 45 tension 63' of lever 58 to cam the latter outward so that latch extension 61 is replaced on projection 62 and stop extension 62' is positioned 50 in the path of lug 55' of stop plate 54 to halt rotation of shaft 6 until the receipt of another start impulse on magnet 70.

It will be apparent to those skilled in the art that the selector mechanism so far described may be used for a wide variety of remote control, selective switching and other operations. As 55 shown for the purpose of illustration, however, this mechanism is applied to a printing telegraph receiver.

Cooperating with the selector and levers is a stop wheel assembly generally indicated at 101 60 which has thirty-two separate stop positions that are disposed in rows, each row corresponding to a cooperating stop lever; the rows of stops cooperating with the stop or selector levers progressively doubling in number; the row cooperating 65 with stop lever 39 having one stop; 41, two stops; 42, four stops; 43, eight stops; and 44, sixteen stops. Stop 102 which cooperates with stop lever 39 is placed 180 degrees from normal stop 88. Stop 88 cooperates with stop lever 46 70 which it engages in the normal or rest position of the apparatus.

Stop wheel assembly 101 is attached to shaft 7 75 preferably in the same manner as cam assembly 31, i. e., by collar and pin arrangement 32. In addition to stop wheel 101, shaft 7 also carries

typewheel 103 secured thereto by suitable means, typewheel 103 having two rows of characters thereon. As before described, shaft 7 is frictionally driven by motor 1 through gear 5 and friction clutch 9. Gear 5 preferably rotates at approximately two and one-half times the speed of gear 3. Selective operation of the various selectors or stop levers will permit the typewheel to assume any one of thirty-two positions including the normal stop or rest position of which twenty-six positions are each provided with a letter of the alphabet. However, the typewheel will be provided with character markings only at certain positions and will assume the remaining positions during operation of the several functions in a manner to be described. 15

To set typewheel 103 in a selected position, as for example, for the selection of the letter A, the stop lever 39 will be operated first in the manner previously described, to place its latch extension 87 in the path of stop 102 of stop wheel assembly 101 which is placed 180° away from the normal stop shown at 88, thus permitting stop assembly 101 and typewheel 103 to make one-half revolution. The operation of stop lever 39 will release the lever 46. The second signal to select the letter A will cause stop lever 41 to be operated to place its latch extension 87 in the path of a finger located in the second row of stops of stop assembly 101. The operation of the lever 41 as 30 described will release lever 39 so that its projection 87 will release stop assembly 101 permitting it and typewheel 103 to turn one-quarter of a revolution. 25

As previously described for the selection of the letter A the stop levers 42, 43 and 44 are not operated to place their respective projections 87 in the path of the stop fingers. Therefore stop assembly 101 and typewheel 103 will remain in the position set by stop lever 41. The letter A 40 is so located on the typewheel 103 that it is now set in position for printing.

By setting the stop levers in various combinations, stop assembly 101 and typewheel 103 will be set in any of thirty-one positions, the thirty-second position being the normal start position, that is when stop 88 is in engagement with lever 46. For a more detailed description of the aforesaid operation, reference may be had to my co-pending application Serial No. 18,888. 50

As in my co-pending application Serial No. 18,888 the rotary travel of the finger element of the stop wheel designated herein as 101', and in the co-pending application as 77, decreases progressively as the successive stop levers are 55 operated, and likewise as in the previous application above referred to, the typewheel starts rotating immediately after the letter is printed and before the cycle operation representing that letter is completed so that normally the typewheel is always at zero position; all of which makes possible the operation of the present machine without devices for storing signals as they are received and without devices for overlapping the selection and the printing into the following letter. As pointed out in the co-pending application Serial No. 18,888, stop finger assembly 101' and typewheel 103 are not always in the zero position when the first selecting signal of a letter is received on magnet 70. This will occur 60 when there is no appreciable time interval between the groups of signals. However, due to the increased speed ratio of stopwheel assembly 101 over that of selector cam assembly 31 there will always be sufficient time for stopwheel as- 70 65 75

sembly 101 to assume its correct selected position.

The printing of the selected letter is accomplished in the following manner.

- 5 Typewheel 103 is inked by ink roller 104, omitted from Figure 1 for the sake of clarity, but shown in Figures 2, 3, 4 and 5. Roller 104 is mounted to rotate in a bracket 105 pivoted on plate 12 at 106 Fig. 4, roller 104 being held 10 against typewheel 103 by spring 107 secured to plate 12 at 108. Record paper 109 passes under typewheel 103 through guide 111 mounted on carriage 112 which is pivoted in bracket 113 secured to plate 12 by screws 114. Print lever 115 is pivoted on stud 116 mounted in carriage 112 and has extending from the inner side pin 117 which is engaged by bifurcated end or fork 118 of a bell crank 119 mounted on stud 121 attached to plate 12 as shown in Figures 1 and 3, 15 and is pressed against printing cam 122 by spring 123. Cam 122 has notch 124 therein into which crank 119 is pulled by spring 123 to actuate pin 117 and print lever 115. Fork 118 permits of oscillation of carriage 112 while maintaining its 20 engagement with pin 117.

Feed pawl 125 is mounted on printing lever 115, and engages ratchet or feed wheel 126 having a suitably knurled roller 127 secured thereto. Pressure roller 128 mounted on bell crank 129 30 pivoted at 131 cooperates with roller 127 to engage and advance record paper 109. Retaining pawl 132 is attached to carriage 112 to cooperate with ratchet 126 in advancing paper 109.

- Lug 134 is provided on the end of lever 115 35 to engage notches 135 cut in slotted bracket or locking plate 136 fastened to plate 12 by suitable screws. Between notches 135, bracket 136 has a double tapered surface 138 to facilitate transfer of lug 134 from one notch to the other. 40 This arrangement is provided to aid in the carriage shift to be later described and to accurately position lever 115 and carriage 112 with respect to the two rows of type on type-wheel 103.

When the typewheel is positioned after the selecting operation, shaft 6 continues to rotate and bell crank 119 drops into notch 124 on cam 122 by the action of spring 123, forcing print lever 115 upward so that hammer 133 thereon presses record paper 109 against typewheel 103 by an 45 overthrow action created by a slight space in bifurcated part 118 of bell crank 119 and immediately thereafter moving slightly away from record paper 109, freeing the same from type-wheel 103. As printing cam 122 continues to 50 revolve, it forces bell crank 119 downward and, by carrying with it feed pawl 125, feeds the paper forward, reverse feed being prevented by locking pawl 132.

It is to be understood that the foregoing described mechanism is capable of a wide variety of applications other than those described herein by way of illustration, and it is intended that such uses of the mechanism be within the scope of the present invention.

- 55 Typewheel 103 is provided with two rows of characters, one comprising letters and the other figures. To shift the printing from one row to the other, T-shaped crank 139 is pivoted on bracket 141 through stud 142 and attached to 60 carriage 112 by link 143 through pivot screw 144. Link 143 is secured to carriage 112 by pivot screw 145. To operate T-shaped crank 139 and thereby shift carriage 112, two selector discs 146 and 147 are provided on shaft 7. Cooperating with selector discs 146 and 147 are two shift levers

148 and 149, respectively, pivoting on a stud 151 secured in plate 12. These levers operate in like manner so that it will be necessary to describe only the operation of one.

With reference to Figure 5, shift lever 148 is 5 pivoted on stud 151, its upper end being provided with extension 152 which may drop into notch 153 of selector disk 146. The other extremity 161 of shift lever 148 engages cam 154 on shaft 6 and is normally held in contact therewith by spring 155 attached to lever 148 at 156 and to stud 157 in plate 12. Lower extension 158 of shift lever 148 engages arm 159 of crank 139. A notch 162 is provided in cam 154 to engage extension 161 of lever 148.

15 When the signal impulses for shift condition are received on magnet 65 and shaft 7 is set in a corresponding position by the stop levers and stop wheel 101, notch 153 of disk 146 will be moved to a position to receive projection 152 20 of lever 148, and as cam 154 continues rotation, projection 161 of lever 148 will go into notch 162 on cam 154 through the action of spring 155. The lower end of lever 148 at 158 will move clockwise to engage arm 159 of T-crank 139 to 25 shift carriage 112.

To prevent printing when shifting, a finger 163 is secured to shaft 7 to rotate therewith and is positioned so that it will engage projection 164 on print lever 115 when carriage 112 is to 30 be shifted. While the print lever 115 will be raised by crank 119 when the shift function occurs, hammer 133 will not strike the paper due to projection 164 coming into engagement with finger 163.

35 Finger 163 is one of four fingers mounted on shaft 7 to rotate therewith. Fingers 163 are so disposed in relation to the position of the type-wheel that one will be positioned to engage projection 164 whenever a function is selected to 40 thereby prevent printing.

To operate a function in the figure shift position, such as ringing a bell, closing a contact, or any other operation that may be desired, finger 165 is provided in a position where it will 45 contact projection 164 only in figures shift position.

In operating a signal bell, selector disk 166, provided with slot 167 positioned in the selective position for operating the signal bell, is 50 mounted on shaft 7. Cam 168, similar to cam 154 is mounted on shaft 6. Lever 169, similar to T-shaped shift lever 148, is pivoted on stud 151. Unlike lever 148, lever 169 has two lower extensions 171 and 172. Extension 172 is a bell 55 clapper. Extension 171 is placed so that it will engage with lug 173 forming part of link 143 when the shift is in the operating position to print letters, thereby preventing clapper 172 from striking bell 174 when a letter is to be 60 printed. When carriage 112 is shifted to print figures, lug 173 is out of the path of extension 171 and at that time clapper 172 will strike bell 174 when the signal selection is received on magnet 65.

65 While the function mechanisms just described have been shown in connection with a typewheel printer, it is to be understood that such showing is only by way of example and other applications of the disclosed mechanism are intended 70 as coming within the scope of the present invention.

Referring to Figures 20 and 21, a preferred form of magnet is therein illustrated. As shown, magnet 65 preferably has a U-shaped core 75

constructed of laminations of iron or other desirable magnetic material, coils 176 being pre-wound on forms so that they may be slipped thereover. Pole faces 177, each consisting of two U-shaped magnetic members 178, are fastened to the protruding ends of the core after coils 176 are placed thereon. The U-shaped magnetic members 178 are secured by suitable means such as pins 179. Pole faces 177 serve to increase the pole face area of the magnets and also serve to hold wire coils 176 in place.

Referring to Figure 22, a view of armature lever 63 is there shown as pivoted on stud 64. As shown, lug 62 projects from one side of armature 63, fulcrum 81 being secured to the top thereof in a position to engage the various selector levers in the manner previously described.

In Figures 23 to 30, inclusive, a further preferred modification of the printer of Figures 1 to 22, inclusive is shown. Since the signal receiving and selecting mechanism is the same as in the first modification, the description thereof will not be repeated. Shaft 6 is employed with gear 3 and friction clutch 8. Shaft 7 with friction clutch 9 and gear 5 thereon has typewheel 103 thereon. Gear 4 in the present modification is not only an idler gear but is also utilized in connection with the function operating mechanism in a manner to be later described.

Referring to Figures 23, 25 and 28, paper carriage 193 is mounted on slide bar 194 by suitable fastening means 195. Bar 194 slides in slot 196 in side frame 197. Stud 198 fastened to bar 194 is guided in aperture 199 in side frame 201. Paper carriage 193 is generally similar to carriage 112 of the printer of Figure 1 in that it comprises paper guide 202, paper feed ratchet 203 actuated by pawl 204 and held against reverse rotation by pawl 205. Paper carriage 193 is not pivotally mounted but is secured to bar 194 so that despite the shift position, it is always in a plane normal to the axis of typewheel 103 and parallel to side frame 197. To shift paper carriage 193, bell crank lever 206 is mounted on stud 207 fastened in plate 208 attached to side frame 197. Depending arm 209 of bell crank lever 206 is bifurcated at 211 to engage stud 212 fastened to bar 194. Latch lever 213 is mounted on stud 214 fastened to plate 208 and normally urged clockwise by spring 200. Spring 215, connected to projection 216 on bar 194 and to side frame 197, holds projection 217 on bar 194 against stop 218 as shown in Figure 25 which is the letters printing position.

Latch lever 213 will engage lug 219, forming a part of depending arm 209, when bar 194 is moved to the left, as viewed in Figure 25.

To move carriage 193 into figures printing position, a group of signals comprising a no current start signal, two current signals, one no current signal, and two current signals, and a stop current signal, for example, are received on the selecting magnet and operate on the mechanism controlling shaft 7 to set the latter so that notch 221 in disc 222 will be opposite finger 223 on lever 224 pivoted on stud 220 on side frame 197. Thus as shaft 6 continues to rotate, projection 225 on lever 224 will enter notch 226 of operating cam 227. Lever 224 will then be partially rotated by spring 228 to operate latch 229 composed of two lever elements 230 and 230' fixed to a rotating collar 232 and connected to lever 224 by link 231 to release slide member 233 mounted on lever 206 as

shown in Figure 25. Member 233 is slideable on bar 206 by means of screw and slot connections 234.

Cam 235 is mounted on idler gear 4 which rotates continuously at a speed approximately twice that of selector shaft 6. When slide member 233 is released spring 236 acts upon it through lug 237 to place roller 238 in the path of cam 235, spring 236 also being fastened to lever 206 at 239. Upon engagement of cam 235 with roller 238, lever 206 is rotated to move slide bar 194 to the left, as viewed in Figure 25, whereupon latch lever 213 engages lug 219 to hold bar 194 in the set position. Face cam 241, also fastened to gear 4, will engage projection 242 of slide member 233 after the latter has been subject to operation by cam 235 and move member 233 to the right, as viewed in Figure 25, until the latter is again engaged by latch 229.

During the operation just described, selector shaft 6 will have continued to rotate and finger 223 of lever 224 will have been withdrawn from notch 221 in disc 222 thereby freeing latch 229.

To move bar 194 so that carriage 193 will be in the letters printing position, a disc 243 is provided with notch 244 so positioned that when the letters shift signals comprising a no current start signal, five selecting current signals, and a stop current signal are received on magnet 65, it will be opposite finger 245 on lever 246 whereupon lever 246 will be operated by spring 247 and cam 248 with notch 249 in the same manner as the operation of lever 224. Lever 246 when operated will engage upper projection 251 of latch lever 213, pressing lever 213 down to disengage it from lug 219 whereupon spring 215 will move bar 194 and carriage 193 into letters printing position.

The paper feeding mechanism is mounted in the paper carriage 202 in the same manner as 40 in the tape printer previously described. The printing hammer 261, however, is mounted on shaft 252 which has a bearing at 253 in paper carriage 193 and a bearing at 254 in plate 208. Shaft 252 reciprocates with the shift and unshift operations of paper carriage 193. Print operating bell crank 255 is secured to shaft 252 and is provided with lug 256 that engages operating cam 257 mounted on selector shaft 6. Bell crank 255 is also provided with extension 258 arranged to engage stop fingers 259 mounted on shaft 7 whenever a function such as shift, unshift, space or signal is selected to prevent the printing hammer from striking the paper tape to prevent printing when a function is to be operated.

For printing and feeding, hammer 261 is provided on arm 262 secured to shaft 252 with pawls 204 and 205 engaging feed ratchet 203 which has knurled roller 203' thereon against which the paper is pressed by roller 263 mounted on arm 264 held in place by spring 265 and pivoted at 131.

In the present modification it will be noted that print operating bell crank 255 operates to release arm 262 so that it may be swung to printing position by spring 266 secured to the right end of arm 262 at 267 and to carriage 193 at 268. Since arm 262 is fixed to shaft 252 with bell crank 255, the camming action of cam 257 will return arm 262 to its non-printing position.

Referring to Figures 31 to 46, inclusive, a further preferred embodiment of my invention in a page printer is shown. Since the selecting mechanism employed therewith is identical with that previously described in connection with the

20

70

75

- printer of Figure 1, up to the transmission of movement to the shaft 7 from the stop wheel assembly 101, a description of the selecting mechanism at this point is not necessary. For convenience, the reference characters applied to the selector mechanism of the printer of Figures 31 to 46, inclusive, are the same as those employed in the description of the printer of Figure 1 and reference may be had thereto.
- 10 As shown in Figures 31 and 32, the printer about to be described generally resembles a typewriter in that it is adapted to print upon a page rather than upon a tape. Base 281 with upstanding frame 282 supports frame 299 extending across the machine and supporting carriage supporting tracks 283 and 284 for reciprocating carriage 285. The latter is supported from track 284 by ball bearings 286 and track 287, rollers 288 mounted on the carriage on shaft 289 to ride 15 on track 283. The outer ends of shafts 289 have L-shaped clips 291 secured thereto to engage the underside of track 283 and hold the carriage on the track. A plate 292 is secured to track 284 to engage slot 293 in track 287 for a like purpose.
- 20 25 A platen roller 294 is carried in carriage 285 in a manner common in typewriters and is provided with ratchets 295 and pawls 296 for line advance in a manner to be described. Platen roller 294 is formed with handle 297 at one end and is supported by two L-shaped brackets 298 secured to track 287 by suitable fastening means. Spring 300 pressed paper holders 308 are provided to cooperate with platen roller 294, paper shield 309 also being provided for guiding paper into the 30 printer and keeping it free of the operating mechanism.
- 35 To effect vertical shifting of platen roller 294 and its supporting means, shift frame 299 is provided with connecting means 301 to track 284 and connecting means 302 to track 283, as shown in Figure 35. Thus when shift frame 299 is moved vertically, tracks 283 and 284 are carried therewith to move platen roller 294 and its supporting means.
- 40 45 Frame 299 has lugs 303 at its lower end with pins 304 therein arranged to slide in and be guided by apertures 305 in lugs 306 integral with frame 282. Springs 307 are provided between lugs 303 and lugs 306 to normally maintain frame 299 in its uppermost position, nuts 308 being secured to the lower ends of pins 304 which are threaded. Frame 299 is also guided for vertical movement by lugs 309 secured to frame 282 by suitable means.
- 50 55 Stop wheel 101 which is fixed to shaft 7 is preferably geared in a 3 to 1 ratio to spider 311 mounted on shaft 312 carried by hub 313 on arm 314 secured to the printer, shaft 312 having worm gear 315 to engage worm 316 on shaft 7.
- 60 65 Spider 311 comprises three projecting lugs, each of which is slotted to receive a lever 317 which is pivoted at 318. A projection 321 forming part of each lever 317 is normally pressed against a face of the spider by collar 323 of spring 322. Spring 322 which is mounted on a projection of the spider shaft 312 is held thereon by a washer 324 and nut 325.
- 70 75 This arrangement permits of a pivoting of levers 317 about pivots 318, the pivoting being limited by spring 322 and contact of projections 321 with a face of the spider 311. Spider 311 is rotated to bring one of fingers 317 into selected position opposite an operating bar 326 by positioning stop wheel assembly 101 in a manner previously described in connection with the setting
- of typewheel 103. Three fingers 317 are provided by reason of the 3 to 1 ratio between stop wheel 101 and the spider 311.
- When one of fingers 317 is positioned opposite an operating bar 326, setting bail 327 mounted on arms 328, in turn pivoted on shaft 329 and having an extension 331, is operated by extension 331 dropping into notch 332 in cam 333 mounted on shaft 6. Immediately thereafter extension 334, also pivoted on shaft 329, and carrying operating bail 336, drops off ledge 337 of cam 338 mounted on shaft 6.
- The function of the elements to set and operate an operating bar 326 is shown in the various positions in Figures 36 to 39, inclusive. Figure 36 shows the normal or rest position of the elements. Figure 37 shows how a selected finger 317 when operated by setting bail 327, places an operating bar 326 in the path of operating bail 336 by contacting upper cam face 343 of operating bar 326 and forcing bar 326 downward as finger 317 is pivoted about pin 318 by bail 327. Figure 38 shows setting bail 327 returned to its normal position and operating bail 336 in engagement with operating bar 326. Finger 317 is returned to its normal position by spring 322 and collar 323 acting on lug 321.
- Figure 39 shows operating bail 336 in its final position and operating bar 326 out of engagement with operating bail 336 which occurs when a selector type bar 339, due to its inertia, has completed its printing stroke and carried operating bar 326 slightly beyond the travel of operating bail 336, thereby disengaging bar 326, the position of bar 326 during actual printing being shown in dotted lines (Fig. 39). When this disengagement takes place spring 341, connected to bar 326 at 342 and to frame 282, is arranged to lift the operated end of operating bar 326 slightly upward to permit it to return over the top of operating bail 336 to normal position as shown in Figure 36.
- It will be noted that the setting of a selected operating bar 326 and the restoring to normal of its selector finger 317 is accomplished in a short interval of time, and it is not necessary for finger 317 and spider 311 to remain set after bar 326 has been engaged by operating bail 336. This is necessary as stop wheel assembly 101 is held for only a minimum of time so as to permit it to again revolve to the next selected position without waiting for complete operation of the printing function. Operating bail 336 engages operating bar 326 immediately after the latter is positioned, engagement between these two members being maintained by having slight undercut faces 344 and 343 on their respective engaging surfaces.
- Type bars 339 are pivoted on wire 345 and are supported in a manner common in typewriters by arcuate shaped bracket 346 secured to frame 282 by suitable means. Each type bar has two characters thereon as shown at 347 and each is provided with gear teeth 348 arranged to engage racks 349 on operating bars 326 which are held in engagement with gear teeth of the selected type bar 339 by a semi-circular ring 351 secured to frame 282 by suitable means.
- In accordance with the setting of stop wheel assembly 101, fingers 317 can assume thirty-two selected positions. Corresponding with these selected positions, thirty operating bars 326 are provided, twenty-six of these operating type bars, the other four operating the space, shift, unshift and line feed functions. No operating bars are

provided for the carriage return or the blank selection.

The twenty-six operating bars for the type bars each have an extending lug 352 that engages universal bail 353 mounted on link 354 that is supported in turn for rotation on lug 355 in the frame of the printer by pins 356. Extending finger 357 attached to universal bail 353 is guided in slot 358 in which bars 326 operate to give universal bail 353 a parallel motion when operated. Link 359 connects universal bail 353 with ribbon vibrator link 361 which functions in the normal manner common to typewriters. Link 361 is pivoted at 362 to a lug 363 secured to track 283 and is pivoted at 364 to ribbon vibrator 365, the ribbon vibrator being guided by S bracket 366 secured to the printer frame at 367.

Bell crank 368 pivoted on pin 369 is provided with link 371 that extends over the top of spacer 20 pawl 372. Spacer pawl 372 is mounted on friction bearing 373 forming part of bell crank 374 pivoted at 375 which has depending lug 376 engaged by bifurcated extension 377 forming part of operating bail 336 and operating therewith. Spacer 25 pawl 372 has projection 378 thereon to engage teeth 379 of spacing rack 381 fastened to track 287 in any suitable manner. Spacer pawl 372 also has projection 382 arranged to engage projection 383 on a latch member to be described to 30 keep pawl 372 in alignment with the rack 381.

In normal or rest position of the machine, the parts are positioned as shown in Figures 31, 32 and 33, that is, operating bail 336 has just dropped off ledge 337 of cam 338, has operated 35 a type bar 339, or performed some other function, and has started on its return motion, cams 333 and 338 on shaft 6 being held stationary by stop 62'. When stop 62' releases shaft 6 to start selection of a following letter, cam 338 acts to 40 restore operating bail 336 and in so doing bell crank 374 is operated to space paper carriage 285 to which spacing rack 381 is connected, through spacing pawl 372 a distance of one letter space. A retaining pawl 384 with tooth 385 holds 45 the paper carriage in set position so that spacing pawl 372 may be moved forward for further spacing in the following manner.

When extension 334 again falls off ledge 337, operating bail 336 will again engage one of operating bars 326 and corresponding lug 352 will engage with universal bail 353. Bell crank 368 accordingly will be operated through projection 386 and pin 387 on bail 353 to return spacing pawl 372 to a position to engage the next tooth of spacing rack 381 through link 371. In traveling back over the teeth of spacing rack 381, spacing pawl 372 will be pushed upward and remain in that position due to the friction in bearing 375. After spacing pawl 372 has passed 55 into position for the next tooth, link 371, which is attached to bell crank 368, will engage spacing pawl 372 to push it downwardly for engagement with a tooth in spacing rack 381 where it will remain so that when bell crank 374 is operated in the opposite direction, spacing pawl 372 will engage with spacing rack 381 and perform its spacing function as previously explained.

Only those operating bars 326 that operate the twenty-six type bars 339 and the one operating the space are provided with lugs 352. Operating bars 326 which operate the shift and other functions do not have lugs 352 and therefore will not set spacing pawl 372 into spacing rack 381 for spacing paper carriage 285 whenever a function is operated. In Figure 32, only a few

of the operating bars are shown, the balance being omitted for the sake of clarity of the drawings. In connection with bars 326, it will be noted that their movement is limited by depending frame or guide 388 on arm 314, frame 388 having slots therein, the walls of which engage projections 389 and 391 on bars 326.

Spacing rack 381 is provided at its lower face with gear teeth 392 that engage with gear teeth 393 on carriage return spring drum 394. Retaining pawl 384 which is pivoted on stud 395 is connected by link 396 to carriage return operating mechanism shown in Figure 34, comprising bell crank 397, lever 398, selector disk 399 mounted on shaft 7, operating cam 401 mounted 10 on shaft 6, and a spring 402 secured to the printer frame. When stop wheel assembly 101 is set for the carriage return selection, slot 403 in selecting disk 399 is set opposite finger 404 on lever 398. During completion of the rotation of 20 shaft 6, notch 405 in operating cam 401 passes under finger 406 also on lever 398, which is forced into notch 405 by spring 402, finger 404 entering slot 403. Extension 407, also on lever 398, at this time engages stud 408 on bell crank 25 397 to operate it thereby raising retaining pawl 384 and spacing pawl 372 from engagement with teeth 379 of spacing rack 381 and permitting carriage return spring drum 394 to return paper carriage 285 to its starting position. Spacer 30 pawl 372 is raised by the right end of retaining pawl 384 engaging the underside of projection 382.

To insure paper carriage 285 fully returning to its starting position, latch lever 409 is provided to lock retaining pawl 384 and spacing pawl 372 in the carriage return position until pin 411 on paper carriage 285 strikes latch lever 409 to disengage it. Lever 409 is pivoted to the printer at 412 and has notch 413 which engages 35 lug 414 on pawl 384, lever 409 being urged in clockwise direction by springs 415 secured to the frame. It will be apparent that lever 398 can be operated only when stop wheel assembly 101 is positioned for a particular function selection 40 and that for any other selection finger 404 will rest on the periphery of selection disc 399 whenever finger 406 passes over notch 405 of cam 401.

To operate the space function, no change in operation is required except that with the particular operating bar 326 that is selected by the space function, type bar 339 is omitted.

With reference to the mechanism for vertically shifting the paper carriage, post 416 is attached to shiftable frame 299. Stop 417, secured to frame 282, is placed adjacent the end of lever 418 and post 416 to limit upward motion of frame 299. Lever 418 is pivoted on stud 419 which is mounted on frame 282. A sliding member 421 having a stop projection 420, a finger 60 423 and a roller 422 is mounted to slide on lever 418. Latch lever 424 normally holds sliding member 421 in engaged position against the tension of spring 425 secured to sliding member 421 at 426 and to lever 418 at 427.

When stop lever assembly 101 is set for a shift function selection, one of fingers 311 is positioned opposite operating bar 326a. Extension 428 on bar 326a will engage with bell crank lever 429 pivoted at 431, and lift latch lever 424 out of 70 engagement with sliding member 421, permitting member 421 to slide forward under the influence of spring 425 and place roller 422 in the path of cam 423'. Bell crank 429, as viewed in Figure 43 is urged in a clockwise direction by 75

spring 430 secured to the printer to maintain latch 424 in a lowered position except when bar 326a is operated.

Cam 423' is constantly driven by motor 1 through its connection to shaft 432 and gear 433 in engagement with worm 2 on the shaft of motor 1, shaft 432 being suitably supported in the printing frame as shown at 434 and 435. Cam 423' rotates at a speed approximately twice that of gear 3, so that for every revolution of shaft 6 whenever it is driven by gear 3, cam faces 436 and 437 on cam 423' will pass at least once under the lever or other member to be operated thereby. Depending on the position of cam 423', roller 422 may either first strike the face of cam 423' or be immediately positioned over it. If it strikes the face of cam 423', it will ride against it until it can slide over its edge. In either case, cam face 437 will strike roller 422, moving it upward, and the extension of lever 418 which is in engagement with post 416 downward thus moving frame 299 downward where it is held by latch lever 438 engaging extension 439 forming part of frame 299. Latch lever 438 is pivoted to frame 282 at 441 and is urged in counter-clockwise direction by spring 442. As the cam 423' continues to rotate, cam face 436 engages return finger 423 and pushes sliding member 421 back into a position where it will be again latched by latch member 424 as shown in Figure 42, thereby taking roller 422 out of the path of cam 437. Lever 418 can then return to its normal position as shown in Figure 40, regardless of whether or not frame 299 re-35 turns to the position shown.

The unshift is operated when the corresponding selection sets stop wheel assembly 101 so that a finger 317 engages operating bar 326b whereupon extension 443a on bar 326b operates latch lever 438 to disengage it from lug 439 thereby permitting springs 307 to return frame 299 and the paper carriage to the position shown in Figures 32, 33 and 40.

The line feed function is operated from cam 423' in a manner similar to the operation of the shift function, the parts being the same with the exception that latch lever 444 is operated through lever 448, shaft 449 and lever 452 by operating bar 326c when it is selected by one of the fingers 317. Roller 446 is attached to sliding member 447, mounted on lever 445 that is normally held against stop 500 by spring 501. When bar 326c is operated, lever 448 is rotated to rotate shaft 449 supported in lugs 451 on the printer frame, lever 452 being raised to rotate latch 444 clockwise and release sliding member 447. Roller 446 is thus placed in the path of cam 423' and lever 445 rotated clockwise to draw down link 453. Through crank 454 pivoted to the frame at 455 and crank 456 pivoted to the carriage at 457, line feed pawl 296 is actuated to turn the platen roller 294.

To feed and reverse inking ribbon 458 the mechanism shown in detail in Figures 31, 33, 45 and 46 is provided. Ribbon 458 is wound on spools 459 in a manner common in typewriters. Each of spools 459 is mounted on a shaft 461, which is provided with gear 462 at its lower end. Shafts 461 are mounted to rotate in bracket 463 secured to frame 282 at 464, bracket 463 having extensions 465 and 466 for support of the reversing mechanism to be described. Shaft 467 is mounted in a U-shaped frame 468 pivoted at 469 on extension 466 of bracket 463 of the ribbon feed mechanism. Gear 471 is secured to shaft

467 and is driven by shaft 472 and pinions 473 and 474 from shaft 6. Shaft 467 is provided at each end with a gear 475 and is positioned in gear 471 so that when frame 468, in which it has its bearing is rotated on pivot 469, only one of gears 475 will at any time be in engagement with a gear 462. Gears 462 are so arranged with relation to one another that ribbon 458 will wind on a spool 459 when its gear 462 is driven by a gear 475. 10

Ribbon reverse control fingers 476, one for each spool 459, are mounted on shaft 477 supported by extension 465 and are normally held against the rolled ribbon by double acting spring 502 which contacts extensions 478 of fingers 476. Each of ribbon reverse control fingers 476 has a second extension 479 which bears slidable body member 481 normally pressed against bearing face 482 by spring 483. Gear 471 has two cam faces at each side, one of which is peripheral cam 484, and the other a side face cam 485. 15

Whenever ribbon 458 is unwound from one of spools 459, corresponding ribbon reverse control finger 476 will be in a position so that its attached lower extension 479 and slidable member 481 will be opposite recessed portion 486 in bearing face 482 and slidable member 481 will be forced into this opening by spring 483. Side cam 485 on the corresponding side of gear 471 will engage with member 481 thereby rotating gear 471 about pivot 469 to move shaft 467 and gears 475 to disengage the gears 475 and 462 which have been in contact and bring the opposite gear 475 into contact with corresponding gear 462 to thereby reverse the motion of ribbon 458. Detent spring 486' mounted on depending extension 487 of bracket 463 is provided to hold frame 468 with the selected shaft and gear in set position through engagement with projection 488 on frame 468. 25

After side face cam 485 has repositioned the shaft 467 to reverse the ribbon, peripheral cam 484 will engage sliding member 481 to push member 481 outward to a position where it will again ride on bearing face 482. This positioning of member 481 will probably take place several times before inking ribbon 458 is sufficiently wound on ribbon spool 459 to push finger 476 out sufficiently so that sliding member 481 will definitely engage with and remain on bearing face 482. 30

Referring to Figures 47 to 50, inclusive, which show the application of the selector herein described to a code bar assembly, stop levers 39, 41, 42, 43 and 44, are each provided with an extending lever 491 which is normally held against lever 496 by a spring 503. In this modification, a separate latch 492 is provided for each of the levers when normal stop lever 46 is not used. Release lever 493 operates in a manner similar to release lever 48 (Figure 2) and when operated acts on all latches 492 to release all levers that have been set up by the previous selection. It should be noted that in this modification the stop levers remain set on latch levers 492 as they are set up which is unlike the operation as previously described in connection with setting of stop wheel assembly 101 wherein the first positioned stop lever is released by setting of the subsequent one so that never more than one stop lever is in set position. 35

Again referring to Figure 47 when the stop levers are set for selection of a letter to be printed, corresponding levers 491 are moved to place their face ends in the path of corresponding code bars 494. Those of the levers 491 not se- 40

lected will be underneath and out of the path of the corresponding code bars 494. Immediately after the setting of the entire group of levers 491, registering detent 495 is lifted and setting lever 496 is operated to move all of the levers 491 in a clockwise direction whereby the selected levers 491 will move corresponding code bars 494 into the selected position whereupon the registering detent 495 will return to normal locking position 10 by the means of the spring secured thereto, holding all of the code bars 494 in the selected position. Code bars 494 are provided with springs 497 which will hold all unselected code bars 494 against stop 498. After code bars 494 assume 15 their selected position as above described, a set of operating bars 499 are placed against code bars 494 and one of these will enter a slot which is aligned by the setting of code bars 494. Thereafter operating bar 499 will operate a type bar 20 to print a letter or perform any other function assigned to it. No mechanism is shown for operating registering detent 495 or lever 496 or for positioning or carrying out the operation of operating bars 499 as such devices are common 25 in the art.

In Figure 51, wherein the spider and selecting arms of Figures 36-39 inclusive are shown, a manner of employing the selecting mechanism of this invention in controlling one or a series of 30 electrical contacts or switches is shown. For the purpose of illustration, a supporting member 504 is shown secured to arm 314, member 504 supporting a contact 505 of a switch and supporting a spring arm 506 at its lower end, arm 506 being 35 suitably insulated from member 504. Arm 506 supports a contact 507 disposed opposite switch contact 505 and is of a length to be urged into a position where the contacts 505 and 507 will meet by a lever 317 when the latter is actuated 40 by bail 327. When the bail 327 is released, arm 506 by reason of its resiliency springs outward to disconnect the contacts. Obviously many other arrangements can be employed other than that shown and it is to be understood that the 45 showing is only by way of illustration and is not to be understood as limiting. By the arrangement of a series of switches in the same manner as operating arms 326 are arranged, it is evident that a selection system of large capacity can 50 be obtained.

Referring to Figures 52, 53 and 54, a preferred modified form of typewheel inking device is there illustrated which is particularly adapted for use with the printers of Figures 4 and 28. The modification as shown embodies a number of the elements shown in Figures 4 and 28 such as typewheel 103 mounted on shaft 7 and printing lever 115 with hammer 133, all of which are operated in a manner previously described.

60 In lieu of inking roller 104 of Figures 4 and 28, an endless ribbon 521 is positioned to pass around and under typewheel 103 in a guide or shield 522 suitably secured to frame 11 as by the screws shown. Guide 522 is spaced from typewheel 103 65 to prevent contact of ribbon 521 therewith except when caused by hammer 133 acting through an aperture in guide 522. From guide 522, ribbon 521 passes over idler roller 523, tension roller 524, inking roller 525, and idler roller 526, 70 idler rollers 523 and 526 being supported on suitable studs projecting from frame 11. Inking roller 525 is mounted to rotate on a suitable shaft as shown journaled in the printer frame and is driven from shaft 6 by a gear train comprising 75 gear 527 mounted on the same shaft as inking

roller 525, gears 528 and 529 mounted on one shaft to rotate together and gear 530 secured to shaft 6. By the gear arrangement shown, the gearing ratio between shaft 6 and inking roller 525 is in a reduced ratio.

5 Tension roller 524 is mounted to rotate on a stud secured to the end of curved lever 531 pivoted on the stud mounting idler roller 526 as shown in Figure 54. Spring 532 (Figure 52) attached to lever 531 and frame 11 by stud 533 10 urges lever 531 in a clockwise direction with sufficient force to press ribbon 521 against inking roller 525 sufficiently hard to drive the ribbon and at the same time replenish it with ink.

This modified method of inking is preferred 15 over that shown in Figure 4 where typewheel 103 is inked directly by ink roller 104 for the reason that due to the high speed reached by typewheel 103 in assuming its selected positions, the extra 20 power necessary for driving an ink roller which rides on the typewheel places an undesirable amount of strain on friction clutch 9. As evident from Figure 52, guide 522 maintains ribbon 521 free of contact with typewheel 103 except when hammer 133 is operated, and the drive of ribbon 521 is entirely from shaft 6, thus imposing no 25 load on shaft 7 which carries typewheel 103.

The invention may be embodied in other specific forms without departing from the spirit or essential characteristics thereof. The present 30 embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

35 What is claimed and desired to be secured by United States Letters Patent is:

1. In a selector mechanism, a plurality of selector members each of said selector members being arranged to pivot about a plurality of points, movable fulcrum means arranged to be operable to select the points about which said selector members pivot to effect selective positioning of 45 said selector members, and means to return each of said selector members to its original position upon the pivoting of another member.

2. In a telegraph receiver; recording means; selector mechanism for converting received signals into mechanical operations comprising a group of selector members, each floating on a fixed bearing at a point intermediate its two ends; a group of cams for operating said selector members in succession and in timed relation with the received signals; and magnet operated means to change the point of fulcrum of said selector members in accordance with the nature of the received signals to thereby position said recording means for selecting and recording a character.

3. In a telegraph receiver; selector mechanism comprising a plurality of selector levers, each floating on a fixed bearing at a point intermediate its two ends; cams located at one end of said levers to operate said levers in succession; means to hold the opposite ends of said levers in one of two selected positions; a pivoting face on each of said levers; a selective magnet; an armature lever therefor carrying a fulcrum member arranged to engage the pivoting face on a selector lever in one position of the armature lever and thereby change the set position of the selector lever when it is operated by a cam, and arranged not to engage said pivoted face in another position of said armature lever.

4. In a telegraph receiver according to claim 3 wherein said pivoting faces of said selector levers and said movable fulcrum member are formed so that they will lock together when in engagement. 3
5. In a telegraph receiver; recording means; selector mechanism for converting received signals into mechanical operations comprising a group of selector members, each floating on a fixed bearing at a point intermediate its two ends; a group of cams for operating said selector members in succession and in timed relation with the received signals; means for holding said selector members at the ends opposite those actuated by said cams in one of two set positions comprising latch means arranged to act on a previously set selector member to release said member when a subsequent selector member is operated; and magnet operated means to change the point of fulcrum of said selector members in accordance with the nature of the received signals to thereby position said recording means for selecting and recording a character. 10
6. In a telegraph receiver; recording means; selector mechanism for converting received signals into mechanical operations comprising a group of selector members; each floating on a fixed bearing at a point intermediate its two ends; a group of cams for operating said selector members in succession and in timed relation with the received signals; said signals comprising a start signal, a group of code signals, and a stop signal; a stationary stop arranged to be released by said start signal; a stop member carried by said group of cams to engage said stationary stop, said stop member being adjustable for orientation with respect to said cams to vary the starting position of said cams with relation to said selector members; and magnet operated means to change the point of fulcrum of said selector members in accordance with the nature of the received signals to thereby position said recording means for selecting and recording a character. 15
7. In a telegraph receiver; recording means; selector mechanism for converting received signals into mechanical operations comprising a group of selector members, each floating on a fixed bearing at a point intermediate its two ends; a group of cams for operating said selector members in succession and in timed relation with the received signals; character setting means comprising a stop-wheel including rows of stops that progressively double in number, each row cooperating with a selector member to set said stop-wheel in various positions in accordance with received signals; latch means to hold said selector members in selected or unselected position, said members pivoting thereon when not selected; a movable fulcrum arranged to pivotally support said selector members when selected to change the position of a selected member in relation to said latch means; and magnet operated means to move said movable fulcrum in accordance with the character of a received signal. 20
8. In a selector mechanism, a plurality of selector members, each of said selector members being arranged to pivot about a plurality of points, movable fulcrum means responsive to successive signals and operable to select the points about which said selector members pivot to effect selective positioning of said selector members, means to operate said selector members in timed relation with said successive signals, and means to return each of said selector mem- 25
- bers to its original position upon the pivoting of another member. 30
9. In a printing telegraph machine, printing means, means including stop means for positioning said printing means, a plurality of selector levers each pivotally movable about a plurality of points, each of said levers being operable when pivoted about one of its pivot points to directly engage said stop means; for selectively and successively controlling said stop means, means for operating said selector levers, and signal responsive means for controlling the action of said selector levers. 35
10. In a printing telegraph machine, printing means, stop means for positioning said printing means, combined selector and stop levers to control said stop means, means to actuate said selector levers, and means responsive to signals received on said machine to render said levers effective with respect to said stops when operated by said actuating means. 40
11. In a printing telegraph machine, printing means, stop means for positioning said printing means, combined selector and stop levers controlling said stop means, means to move said selector levers when signals are received, and means dependent on the character of the signals received to render said levers effective with respect to said stops when moved. 45
12. In a printing telegraph receiver, printing means, and means for moving said printing means into printing position comprising a pivot, a lever mounted on said pivot in a manner to permit both rotation and displacement about said pivot, a fulcrum movable into selective engagement with said lever, and means controlling said fulcrum in accordance with the signals received. 50
13. In a printing telegraph receiver, printing means, and means for moving said printing means into printing position comprising a pivot, a lever mounted on said pivot to permit both rotation and displacement about said pivot, a stop adjacent one end of said lever, means to normally hold said lever against said stop, means to move said lever away from said stop, a fulcrum arranged to be placed in selective engagement with said lever at a point between said pivot and said lever moving means, and means to control said fulcrum in accordance with the signals received. 55
14. In a printing telegraph receiver; printing means, stop means for positioning said printing means; a pivot; a series of selector members for said stop means mounted on said pivot for both rotation and displacement; a plurality of levers mounted on said pivot for rotation; means to operate one of said levers to release said stop means for operation, to operate another of said levers to place said selector members in signal receiving position, and to operate said selector members; means to render said selector members effective on said stop means when operated; and means for operating said last-mentioned means in accordance with received signals. 60
15. In a permutation code printing telegraph receiver; printing means; stop means for positioning said printing means comprising a series of rows of stops, each row being progressively doubled with respect to the preceding row, one row for each unit of a permutation code by which the receiver is to be controlled; and selector members, one for each row of stops; means to set said selector members in accordance with received signals; and means to operate said selector members and to position said printing means in accordance with the received code signals. 65

16. In a printing telegraph receiver; a magnet responsive to received code combinations of selecting conditions, each preceded by a start condition; a rotatable member; means to rotate said member in synchronism with the received code combinations; means to initiate rotation of said member upon reception of said start condition; a plurality of selector members; a plurality of corresponding cams on said rotatable member arranged to engage said members; means under control of said magnet to engage said members under predetermined conditions whereby said levers are subject to the joint control of said cams and said latter means; and rotating stop means in the path of operation of said levers controlled thereby. 5
17. In a printing telegraph receiver; printing means; a stop member assembly for positioning said printing means; a plurality of pivoted selector levers arranged selectively engageable with said stop member; means for moving said levers selectively into member engaging position comprising a plurality of rotatable cams successively engaging said selector corresponding levers and rotating in synchronism with the received signals; and means operated by the received signals to modify the resultant action of said levers as operated by said cams. 10
18. In a printing telegraph receiver, a shaft, printing means on said shaft, function operating means on said shaft, selector means on said shaft for positioning said printing means and operating said function mechanisms, means for operating said printing means to effect printing thereby, and means on said shaft for preventing operation of said latter means when a function-operating signal is received. 15
19. A stop control mechanism for cooperation with stops on a type positioning shaft of a telegraph recorder comprising a series of independently movable stop engaging levers, an additional stop engaging lever for holding said shaft in normal or start position, a latch member arranged to engage and hold any one of said members in stop engaging position, means to operate said first levers in succession independent of the character of signal received, means dependent upon the character of signal to position said levers in the path of said stops, means to release said additional stop engaging lever upon operation of said latter means, and means to restore said additional stop engaging lever to stop engaging position after an impression has been made from the positioned type. 20
20. A stop control mechanism for cooperation with stops on a type positioning shaft of a telegraph recorder comprising a series of independently movable selector levers, means to operate said levers in synchronism with the reception of the factors of a code signal independent of the character of the factor, and means dependent upon the character of the factor to position said levers in the path of said stops. 25
21. A stop control mechanism for cooperation with stops on a type positioning shaft of a telegraph receiver comprising a series of independently movable selector levers, means to operate said levers in synchronism with the reception of the factors of a code signal independent of the character of the factor, means dependent upon the character of factor to position said levers in the path of said stops, and a latch member to engage and hold any one of said levers in stop engaging position, said latch member being arranged to be released from engagement with one lever by the operation of a succeeding lever. 30
22. A printing telegraph receiver comprising a typewheel, a typewheel drive shaft, a function operating shaft, driving means, means to connect said shafts to said driving means comprising a friction clutch for each shaft, stops on said typewheel drive shaft, selector levers for engaging said stops to position said typewheel in selected printing positions, selector means comprising means on said function operating shaft to operate said levers in synchronism with received signals, and means to effect an impression by said typewheel, said means comprising an operating member on said function-operating shaft arranged to operate said impression means immediately after said lever operating means completes its operative engagement with said levers so that printing is accomplished immediately following selection of a character on the typewheel. 35
23. A printing telegraph receiver comprising a type wheel, a typewheel drive shaft, a function operating shaft, driving means, means to connect said shafts thereto comprising a friction clutch for each shaft, stops on said typewheel drive shaft, stop levers for engaging said stops to position said typewheel in selected printing positions, selector means comprising means on said function operating shaft to operate said levers in synchronism with received signals, means responsive to the character of signal received to place said operating levers in operative engagement with said typewheel stops, and means to effect an impression by said typewheel, said means comprising a cam on said function operating shaft arranged to operate said impression means immediately after said lever operating means completes its operative engagement with said levers so that printing is accomplished immediately following selection of a character on the typewheel. 40
24. In a printing telegraph receiver, a type-wheel operating shaft having stop means thereon, a function operating shaft having selector operating means thereon, means cooperating with said selector operating means and responsive to received signals to position said stop means, function selecting means on said typewheel operating shaft actuated by said stop means, function-operating means on said function operating shaft operated in synchronism with said selector operating means, and function actuating means arranged to be operated by joint action of said function selecting means and said function operating means. 45
25. In a printing telegraph receiver, a type-wheel operating shaft having stop means thereon, a function operating shaft having selector operating means thereon, means cooperating with said selector operating means and responsive to received signals to position said stop means, function selecting means on said typewheel operating shaft actuated by said stop means, function operating means on said function operating shaft operated in synchronism with said selector operating means, function actuating means arranged to be operated by joint action of said function selecting means and said function operating means. 50
26. In a printing telegraph receiver, a shaft having a typewheel thereon, a shiftable carriage for guiding tape adjacent said typewheel, and means to shift said carriage comprising a cam driven in synchronism with received signals and selector means responsive to the character of 55
- 75

- received signals, a crank member connected to said carriage for shifting thereof, and means to operate said crank when said cam and selector means are in predetermined relation to shift said carriage. 5
27. In a printing telegraph receiver, a shaft having a typewheel thereon, a shiftable carriage for guiding tape adjacent said typewheel, means driven in synchronism with received signals to force said tape against said typewheel, means to shift said carriage comprising means driven in synchronism with received signals and selector means responsive to the character of received signals, a crank connected to said carriage for shifting thereof, means to operate said crank when said synchronized means and selector means are in predetermined relation to shift said carriage, and means to prevent operation of said tape-forcing means when said carriage is to be shifted. 10
28. In a printing telegraph receiver, a selector operating shaft driven in synchronism with received signals, a type selecting shaft, means to position said latter shaft in accordance with the character of received signals, and function operating means on each of said shafts arranged to operate when in predetermined relation to one another. 15
29. In a telegraph receiver; recording means; selector mechanism for converting received signals into mechanical operations comprising a group of selector members, each floating on a fixed bearing at a point intermediate its two ends; a group of cams for operating said selector members in succession and in timed relation with the received signals; character setting means comprising a stop-wheel including rows of stops that progressively double in number, each row cooperating with a selector member to set said stop wheel in various positions in accordance with received signals; latch means to hold said selector members in selected or unselected position, said members pivoting thereon when not selected; a movable fulcrum arranged to pivotally support said selector members when selected to change the position of a selected member in relation to said latch means; magnet operated means to move said movable fulcrum in accordance with the character of the received signal; a shaft for supporting said cams; a shaft for supporting said stop-wheel; and function control and operating means on said shaft arranged to operate said function when said shafts are in predetermined relation to one another. 20
30. In a telegraph receiver, a type wheel; a function lever; a selectively positionable function selecting member operable in one selected position to permit operation of said function lever and to prevent motion of the function lever in all other positions; a stop-wheel to position said type wheel and said function selecting member; and a separately rotating cam to operate said function lever when said function selecting member is in said one selected position. 25
31. In a telegraph receiver, a type wheel; a function lever provided with a projection; a function selecting disc provided with a slot to receive said projection in the function selecting position; a stop-wheel to position said type wheel and said function selecting disc; and a cam arranged to operate said function lever when said slot is in alignment with said projection. 30
32. In a telegraph receiver, a type wheel provided with a plurality of rows of type; a stop-wheel to position said type wheel; said receiver including a carriage for a record tape movable into a plurality of set positions so that it may receive printing from either of said rows of type; and a lock to hold the carriage in either of its set positions to prevent shifting the carriage from its set position when the paper is drawn out by hand. 35
33. In a telegraph receiver, a type wheel provided with a plurality of rows of type; a stop wheel to position said type wheel; said receiver including a carriage for a record paper movable into a plurality of set positions so that it may receive printing from either of said rows of type; a print hammer; and a locking member operated by the print hammer to lock the carriage in either of its set positions. 40
34. In a telegraph receiver, a group of code members; selector members arranged to pivot about a plurality of points; combined fulcrum and selecting means to select the points about which said selector members pivot; means on said selector members to set said group of code members into selective alignment to receive one of a group of control or operating bars; and means to complete a selective operation under the control of the selected control or operating bar. 45
35. In a telegraph receiver as claimed in claim 34 wherein said selector members are provided with individual latch members on which the selector members pivot when not selected and on which they latch when selected. 50
36. In a telegraph receiver, selector members arranged to pivot about a plurality of points; combined fulcrum and selecting means to select the points about which said selector members pivot; a code bar operating member for each of said selector members; a plurality of code bars, said code bar operating members being out of the path of said code bars in selected position and in the path thereof when selected; and a bail for moving said code bar operating members to transfer the selected setting of said selector members to the code bars after said selector members are set in accordance with the signals received. 55
37. In a telegraph receiver including a typewriter having operating bars; a stop-wheel for controlling the selecting and setting means for the operating bars of said typewriter; said stop-wheel being provided with rows of stops that progressively double in number; a receiving magnet; and stop means under the control of said magnet to position said stop-wheel in accordance with the received signals. 60
38. In a telegraph receiver as claimed in claim 37 comprising a rotatable member connected to said stop-wheel; a setting finger pivoted on said rotatable member; a group of type bars; and a group of operating bars for said type bars and individual thereto, said operating bars being arranged in an arc and positioned in accordance with the setting positions of said rotatable member and setting finger. 65
39. In a telegraph receiver as claimed in claim 36 comprising a spider arranged to rotate with said stop-wheel; a plurality of loosely mounted arms on said spider; a group of type bars; a group of operating bars for operating said type bars individually and mounted in an arc in the path of said spider arms; and a bail for moving one of said spider arms after it has been set in position by said stop-wheel to operate a type bar operating bar and a type bar. 70
40. In a telegraph receiver, recording means; a selector mechanism for converting received signals into mechanical operations comprising a 75

- group of selector members, each floating on a fixed bearing at a point intermediate its two ends; a group of cams for operating said selector members in succession and in timed relation with the received signals; magnet operated means to change the point of fulcrum of said selector members in accordance with the nature of the received signals to thereby position said recording means for selecting and recording a character; a stop arm on said group of cams; and a stationary stop for said stop arm under control of said magnet, said stop arm being provided with adjusting means to vary the starting positions of said cams relative to said selector members.
15. 41. In a telegraph receiver, recording means; a selector mechanism for converting the received signals into mechanical operations comprising a group of selector members, each floating on a fixed bearing at a point intermediate its two ends; a group of cams for operating said selector members in succession, and in timed relation with the received signals; magnet operated means to change the point of fulcrum of said selector members in accordance with the nature of the received signals to thereby position said recording means for selecting and recording a character; and means to lock said magnet operated means in position until the selective operation is completed regardless of any change in the magnetic character of said magnet.
20. 42. In a printing telegraph receiver, printing means including shift means and paper advance means; electro-magnet means for the reception of signals; selector mechanism including a pivot; a lever mounted on said pivot in a manner to permit both rotation and displacement about said pivot; a fulcrum movable into selective engagement with said lever; means controlled by said magnet for controlling said fulcrum in accordance with the signals received; and means selectively operated by said selector mechanism for selectively operating said printing means and its included shift and paper advance means.
25. 43. In a printing telegraph receiver; printing means including a paper carriage; a spacing rack on said carriage; a spacing pawl normally out of engagement with said rack; electromagnet means for the reception of signals; selector mechanism including a pivot; a lever mounted on said pivot in a manner to permit both rotation and displacement about said pivot; a fulcrum movable into selective engagement with said lever; means controlled by said magnet for controlling said fulcrum in accordance with the signals received; and means selectively operated by said selector mechanism for placing said pawl in engagement with said rack.
30. 44. In a printing telegraph receiver having a shiftable carriage, function operating means, means to select said means in accordance with received signals, a constantly rotating cam, a lever to shift said carriage, a roller on said lever, a spring acting to place said roller in the path of said cam to shift said carriage, a latch normally holding said roller away from said cam, and means operable when selected to release said latch.
35. 45. A printing telegraph receiver comprising a printing wheel with a plurality of rows of type thereon, a reciprocable carriage, means on said carriage to support a tape for printing by said printing wheel, means to shift and maintain said carriage in a plane normal to the axis of said printing wheel and means to operate said latter means when shifting is selected comprising a constantly rotating cam.
40. 46. In a selector mechanism, a rotatable spider having a pivoted selecting arm thereon, a plurality of means arranged to be selectively contacted by said arm, means to rotate said spider and selecting arms to a desired selection, and means to actuate said arm to initiate operation of the selected means.
45. 47. In a printing telegraph machine, printing means, means including stop means for positioning said printing means, selector levers controlling said stop means, means to move said selector levers when signals are received, means dependent on the character of the signals received to render said levers effective with respect to said stops when moved, and means on said levers to lock said latter means in position.
50. 48. In a printing telegraph receiver, printing means, and means for moving said printing means into printing position comprising a pivot, a lever mounted on said pivot to permit both rotation and displacement about said pivot, a stop adjacent one end of said lever, means to normally hold said lever against said stop, means to move said lever away from said stop, a fulcrum arranged to be placed in selective engagement with said lever at a point between said pivot and said lever moving means, and means to control said fulcrum in accordance with the signals received, said lever being notched to engage and lock said fulcrum in its selected position.
55. 49. In a printing telegraph machine, a rotatable selecting assembly and a stop plate thereon, said plate having a plurality of arcuate slots therein for fastening said plate to said selecting assembly whereby said plate may be readily adjusted to orient said assembly.
60. 50. In a printing telegraph machine, a plurality of selector members arranged to pivot about a plurality of points, fulcrum means selectively positioned and responsive to successive signals to select the points about which said selector members pivot to effect selective positioning, a plurality of code bars for selecting a printing operation, means secured to said members arranged to be selectively positioned adjacent said code bars and means operable after positioning of said latter means to selectively operate said code bars through said latter means.
65. 51. In a selector mechanism, a plurality of reciprocable code bars, selector members arranged to pivot about a plurality of points, combined fulcrum and selecting means to select the points about which said selector members pivot to effect selective positioning, means on said selector members to selectively engage and operate said code bars, and means to release said latter means for repositioning upon completion of a selection cycle.
70. 52. A printing telegraph receiver comprising a typewheel, a typewheel drive shaft, a function operating shaft, an inking roller driven from said function operating shaft, an inking ribbon in contact with said inking roller and in spaced relation to said typewheel, and means to place said ribbon in contact with said wheel only when a character is to be printed.
75. 53. A printing telegraph receiver comprising a typewheel, a typewheel drive shaft, a function operating shaft, an inking roller driven from said function operating shaft, an inking ribbon in contact with said inking roller to be driven thereby and means to guide said ribbon around

said typewheel in normally spaced relation thereto.

54. In a printing telegraph receiver, a typewheel provided with two groups of type; a shaft for rotating said type wheel and having rows of stop means thereon that progressively double in number as to the rows; a selector mechanism cooperating with said rows of stops and operable to set the type wheel in various selected rotary positions; mechanism for printing from one or the other of said groups of type including a shiftable printing device and means for selectively positioning said printing device comprising a shifting mechanism operatively associated with said printing device; means for controlling said shifting mechanism carried by said shaft; and cam means connected to and operating with said selecting mechanism for operating said shifting mechanism.
55. A printing telegraph receiver provided with a typewheel having two groups of type; a case shift mechanism; means for setting the typewheel in selected rotary positions comprising a stop wheel connected to said typewheel and always rotating in the same direction, said stopwheel having rows of stops thereon and progressively doubled in number as to the rows; a selecting mechanism for stopping said stopwheels progressively in accordance with the nature of the received signals; control means rotated by said stopwheel; and cam means rotated by the selecting mechanism; said control means and said cam means being conjointly operable to operate the case shift mechanisms.
56. In a printing telegraph receiver, a typewheel shaft having stops thereon that progressively double in number; a selector mechanism comprising a shaft rotated in timed relation with received signals, and a receiving magnet; means controlled by said selector mechanism and said receiving magnet for positioning the typewheel shaft progressively in accordance with the nature of the signals received; and means to select from one of two groups of characters on the typewheel including a shiftable member, and a latching device; mechanism for controlling the operation of said latching device comprising means attached to the typewheel shaft and means associated with the selector mechanism.
57. In a printing telegraph receiver, a typewheel provided with two rows of type; a frictionally driven shaft connected to said typewheel and provided with rows of stops that progressively double in number, a selector mechanism cooperating with said rows of stops to set them and the typewheel in various selected rotary positions; a printing hammer; means to effect printing from either one of said rows of type comprising a shiftable member, means for latching said member in position to effect printing from a selected row of type, and mechanism for controlling said latch-

ing means including control means attached to the typewheel drive shaft and cam means driven in timed relation with the received signals.

58. A printing telegraph receiver provided with a typewheel having two groups of type thereon; a case shift mechanism; means for setting said typewheel in selected rotary positions, comprising a stop wheel connected to said typewheel and always rotating in the same direction, said stopwheel having rows of stops thereon that progressively double in number as to the rows, and selector mechanism for stopping the stop wheel progressively in accordance with the received signals; means for operating said case shift mechanism comprising a control member rotated by said stop wheel, an operating cam rotated by said selector mechanism, and a lever mechanism operable under the conjoint action of said control member and operating cam.

59. In a printing telegraph receiver; a rotating shaft, a plurality of selector cams secured to said shaft; means for frictionally driving said shaft; a stop plate secured to said shaft; stop means for engaging said stop plate to hold said shaft and selector cams against rotation; means operable under the control of received signals to release said stop plate to initiate a selecting cycle, and means on said stop plate for resetting said stop means at the end of said selecting cycle.

60. In a printing telegraph receiver, a rotatable selecting cam assembly; holding means for preventing rotation of said selecting cam assembly comprising a stop plate and a pivoted stop lever; an armature element movable in response to received signals; means on said armature for engaging a portion of said stop lever to hold said stop lever in operative position with respect to said stop plate, said last-named means being movable with said armature to release said lever, and means for moving said lever out of operative position.

61. In a printing telegraph receiver; a selecting mechanism including a receiving magnet having an armature selectively movable into one of two positions, and a plurality of rotatable selector cams; a stop plate associated with said selector cams; friction drive means for rotating said selector cams; means for selectively engaging said stop plate to prevent rotation of said selector cams, said last-named means comprising a pivoted stop lever having one end adapted to engage said stop plate and another end associated with a portion of said armature, said armature portion holding said lever in operative position when in one of its two selected positions; a spring operable to move said lever out of stop plate engagement when said armature is in the other of its selected positions, and means on said stop plate for returning said lever to stop plate engaging position at the end of a selecting cycle.

EDWARD E. KLEINSCHMIDT. 60
